DESIGN FOR A COAT

Jacob J. Kushner, New York, N. Y.

Application March 8, 1938, Serial No. 75,670

Term of patent 3½ years

To all whom it may concern:

Be it known that I, Jacob J. Kushner, a citizen of the United States of America, residing in city of New York, county of New York, and State of New York, have invented a new, original, and ornamental Design for a Coat of which the following is a specification, reference being had to the accompanying drawing, forming part thereof.

Fig. 1 is a front view of a coat, showing my new design.

Fig. 2 is a rear view thereof.

My design is characterized by the specific arrangement of the combined yoke and tucks on the rear portion of the coat as shown.

I claim:

The ornamental design for a coat, substantially as shown and described.

JACOB J. KUSHNER.
